UNITED STATES PATENT OFFICE.

WILLIAM DONEGAN, OF CHICAGO, ILLINOIS.

BOILER ATTACHMENT.

SPECIFICATION forming part of Letters Patent No. 340,200, dated April 20, 1886.

Application filed August 5, 1885. Serial No. 173,594. (No model.)

To all whom it may concern:

Be it known that I, WILLIAM DONEGAN, a citizen of the United States, residing at Chicago, in the county of Cook and State of Illinois, have invented certain new and useful Improvements in Boiler Attachments, of which the following is a specification, to wit:

This invention relates to a device for cleaning boilers; and it consists in certain peculiarities of the construction and arrangement of the same, substantially as will be hereinafter more fully set forth and claimed, whereby the water used in washing out the boiler is drained off without injury to the setting or surroundings.

In order to enable others skilled in the art to which my invention appertains to make and use the same, I will now proceed to describe its construction and operation, referring to the accompanying drawings, in which—

Figure 1 is a perspective view of the front of a steam-boiler with my device in use, and Fig. 2 is a longitudinal section of the same.

a represents the front of a boiler-furnace, and *a'* the boiler inclosed therein, both of which are of the usual or any desired form. These boilers are always made with a hand-hole in the top for the insertion of a hose or similar means of cleaning the dirt and sediment out, and in the end of the boiler-shell, near its bottom, is an opening, *a²*, through which this dirt is removed. In boilers of this kind it is usual to connect the front end of the boiler *a'* with the front of the setting by a plate, *b*, which is known as an "extension-plate," and forms the bottom of the smoke-chamber. As the water from the boiler lies on this plate, it gradually works through onto the fire-brick, generally set below it, and soon loosens them, and causes cracking and injury thereto. In addition to this, all the water which does escape lies on the floor of the furnace-room, and makes it damp and unhealthy. I remedy this as follows:

c represents a broad trough-like chute having its inner end formed with a flange, *c'*, and is secured to the boiler-head by a clamp plate or bar, *c²*, which clasps the flange of the chute and the adjacent edge of the opening *a²*, and is secured by a set-screw, *c³*, which holds the flanged chute tightly against the boiler-head,

and to form a water-tight joint a packing of waste, *c⁴*, or similar material is placed between the boiler-head and the flange of the chute, which, when the device is clamped 55 tightly to place, effectually prevents leakage at this joint. This chute extends through the front plate, *a*, and carries off all water, preventing any from getting onto the plate *b*, as will be seen in the drawings. To retain this 60 water and prevent it from flooding the floor of the room, I suspend from the end of the chute *c* a box or receptacle, *d*, which receives the water as it flows off, and prevents its injury to the floor. This receptacle may, if desired, be of sufficient size to receive and retain all the water used in washing, and afterward removed and emptied; but as this would make it quite large and heavy to handle I prefer to construct it only large enough to receive and prevent the scattering of the water as it flows out of the chute, and having a small opening, *d'*, in its bottom, flanged downward, as at Fig. 2, and under this I suspend a trough, *e*, which is turned in any direction 75 about the flanged opening, and is supported by a yoke, *e'*, hooked over the edge of the box. This yoke may be slid along and the trough turned in any desired direction to conduct the flow of water to the sewer, or any 80 other desired point, and keep the floor of the room dry.

In operation it will be seen that the water is poured into the boiler as usual, and allowed to escape through the opening *a²*, whence it 85 is conducted, as desired, to a receptacle or other point.

Having thus fully described my invention, what I claim as new, and desire to secure by Letters Patent, is—

1. The combination, with a steam-boiler, of a chute having its inner end flanged and a clamp for securing said chute to the escape or drain opening of the boiler, substantially as and for the purpose set forth.

2. The combination, with a steam-boiler, of a chute for directing off the waste water in cleaning, and a receptacle placed under the end of said chute, substantially as and for the purpose set forth.

3. The combination, with a steam-boiler, of a chute detachably secured to its escape-open-

ing, a box or receptacle placed under the end of said chute, and an adjustable trough for conducting the water off to a convenient point, substantially as and for the purpose set forth.

5 4. The combination, with the flanged chute *c* and its securing clamp *c'*, of the box *d*, having a flanged opening, *d'*, and the trough *e* and its adjustable supporting yoke *e'*, all construct-

ed and arranged to operate substantially as and for the purpose set forth.

In testimony whereof I affix my signature in presence of two witnesses.

WILLIAM DONEGAN.
